ANESTHESIA NEEDLE GUIDE

Gerald C. Kohl, Tacoma, Wash.

Application April 12, 1954, Serial No. 422,298

12 Claims. (Cl. 128—215)

This invention relates to a device permitting injection of anesthetics locally into the wall of a cavity within the human body, and in its presently disclosed form constitutes a means facilitating anesthetic injection of the pudendal nerves by access through the birth canal of a female in preparation for child delivery. The invention is herein illustratively described by reference to its presently preferred form as devised for the specific application last-mentioned above; however, it will be evident to those skilled in the art that certain modifications and variations in the illustrated embodiment may be made without departing from the essential features involved.

It is known in the practice of obstetrical medicine that childbirth labor can be eased and shortened by local anesthesia, and it is also established that a successful nerve block for that purpose may be effected by injecting the main trunk of the pudendal nerve subjacent to each lateral wall of the birth canal. However, suitable instruments for accomplishing this result in a fully acceptable and reliable manner heretofore have not been available. The present invention enables this method of anesthetization to be carried out safely, reliably, easily and quickly by a practicing obstetrician.

A specific object of this invention is to provide a simple and effective means for guiding the point of a hollow anesthesia needle through the birth canal and to the correct location on a lateral wall thereof for injecting the main trunk of the pudendal nerve as the latter follows beneath the ischial spine to enter Alcock's canal.

A more specific object is a guide means for the described purpose which may be positioned with great accuracy by a simple technique of palpation, both the guide means itself and the palpation technique used for such positioning being the same for substantially all adult females, regardless of wide variations in the anatomies of different individuals.

Still a more specific object is such an anesthesia needle guide means which automatically limits the depth of penetration of the needle point in the birth canal wall, which protects adjacent tissues from accidental laceration during insertion of the needle to the point of injection, and which in the process of positioning of the guide means irons out or presses aside any gathers of membranous tissue which otherwise might interfere with or deflect the needle point during the actual injection.

Still another object is an instrument of the type described which is reversible in the sense that the same instrument may be used for injecting the left pudendal nerve trunk and also the right pudendal nerve trunk.

In the illustrated form of the invention the novel anesthesia needle guide comprises an elongated retractor having a head portion formed with a recess in the tip thereof adapted to slide along the inside face of a doctor's palpatory finger, in order to guide such head portion to the tip of such finger previously placed by palpation in contact with the spine of the ischium. In order further to facilitate operatively positioning such head portion in a

2

particular relationship to the ischial spine, as will herein-after more fully appear, the retractor head portion has an opening therein which is located between the tip and base of the head portion such that the tip of the palpator finger presses against the ischial spine through such opening and thereby accurately locates such head portion in the desired operative position of the instrument. An elongated needle guide member in the form of a tube is mounted on the retractor such that with the instrument 15 in its operative position as aforementioned one end of this guide tube is accessible for insertion of an elongated anesthesia needle therein exteriorly of the patient, whereas the opposite or distal end of the guide tube is maintained in operative position contacting the correct point on the lateral wall of the birth canal such that the point of the needle in emerging through the distal opening of the guide tube will penetrate the wall to the subjacent location of the pudendal nerve trunk as desired. Preferably two such guide tubes are incorporated in the same instrument, and in a particular positional relationship of their respective distal ends with the locating opening in the retractor head portion. When the retractor head portion is operatively positioned in relation to the ischial spine on one side of the birth canal one of the guide tubes is positioned for injecting the subjacent pudendal nerve trunk on that side, whereas when the instrument is reversed for application thereof to the opposite wall of the birth canal, the other guide tube is positioned for injection of the pudendal nerve trunk subjacent thereto.

As a further feature of the illustrated anesthesia needle guide the head portion of the retractor is of concavo-convex form and as such slides readily into position along the birth canal wall, pressing aside any folds of tissue which may tend to gather and obstruct the correct placement of the distal end of a guide tube or which may tend to prevent penetration of the anesthesia needle tip to the correct depth into the tissues. The locating opening or aperture in the head portion is preferably positioned at the base of the concavity thereof generally between the distal ends of the two guide tubes, and the intermediate portion of the tubes are laterally separated by a distance permitting reception of the palpatory finger of the doctor's hand therebetween in either operative position of the instrument, which has a steadyng effect on the instrument 30 during insertion of the needle. The length of the anesthesia needle chosen is such that the needle ordinarily will be inserted to the hilt in either guide tube 1, so that the needle will penetrate wall tissue to an accurately gauged depth.

These and other features, objects and advantages of the invention will become more fully evident from the following description by reference to the accompanying drawings. It will be understood, however, that the principles of the invention are applicable to the injection 45 of anesthetic substance in the walls of the body cavities other than the birth canal, and that for these other applications, as well as for the illustrated application, certain changes and modifications with respect to the details of construction may be made for convenience or other 50 reasons in the manufacture and use of the particular instrument.

Figure 1 is a side view of the novel anesthesia needle guide.

Figure 2 is a bottom view of the same.

Figure 3 is a perspective view of the guide.

Figures 4, 5, 6 and 7 are operational views showing successive stages in the procedure for anesthetizing by injection of a pudendal nerve trunk using the needle guide.

Referring to Figures 1, 2 and 3, the device illustrated 70 comprises a retractor means 10 having a head portion 12 and a shank or handle portion 14. The retractor means

10 serves as the supporting and positioning means for each of two needle guide members in the form of elongated open-end tubes 16 and 18, which in the two operative positions of the device (i. e. applied to the right and left walls of the birth canal respectively) serve alternately to guide the hollow anesthesia needle to the correct point of injection.

The retractor means head portion 12 is of generally concavo-convex form, its base being joined to the end of the elongated shank portion 14 and its tip having a recess 12a which generally embraces the inside face of the doctor's palpitory finger in a manner and for guiding purposes to be described hereinafter. Between the recessed tip and the base of the head portion 12 is a locating aperture 12b of generally circular form and of a size just ample to permit the tip of the doctor's palpitory finger to press against the ischial spine of the patient through such aperture in the operative position of the guide instrument, as will be more fully explained hereinafter.

The handle or shank portion 14 of the retractor means 10 is of a length and of a form permitting insertion of the retractor head portion 12 into the birth canal and advancing the same into operative position adjacent the ischial spine by manipulation of the instrument conveniently from outside the entrance to the vagina. When in operative position the outer ends of the guide tubes will project out of the vaginal orifice so as to facilitate insertion of an anesthesia needle through such tubes.

In the illustrated form of the device, the retractor shank portion 14 has a jog or offset 14a therein generally intermediate its ends, which offset is provided with two apertures supportingly receiving the respective needle guide tubes 16 and 18 in their mounted position on the retractor 10. In the example the two guide tubes are of upwardly arched or bowed form as viewed in Figure 1. The outer ends of these guide tubes are located near the butt end of the shank 14 and below such shank, as viewed in Figure 1, and after passing through the apertures in the shank offset 14a follow upwardly arched and laterally divergent lines extending along the length of the shank to their distal ends mounted on the head portion 12 at respectively opposite sides of the locating aperture 12b therein. The distal ends of these guide tubes are so located in relation to the aperture 12b that proper positioning of the retractor head portion 12 in relation to the ischial spine places the distal end of one such guide tube in contact with the birth canal wall at a point just above the subjacent main trunk of the pudendal nerve, as hereinafter more fully explained. Preferably the distal ends of the guide tubes 16 and 18 project through retaining apertures in the head portion 12 and a short distance beyond the opposite face of such head portion. The guide tube tips 16a and 18a projecting a short distance beyond the convex face of the retractor head portion will tend to press firmly against and produce some depression of the wall tissue with the instrument in operative position to insure that the anesthesia needle tip projected through the distal end openings will penetrate such tissue without a tendency to slide thereon.

In a practical design the guide tubes 16 and 18 have an internal diameter of about one millimeter and will be capable of receiving and guiding an elongated tubular anesthesia needle of approximately one-half millimeter or less outside diameter for the described purpose. Flexible tubular anesthesia injection needles of sufficient length to inject the pudendal nerve trunks in the described manner by insertion through the guide tubes 16 and 18 are available. Obviously the guide tubes if of curved form as illustrated must be curved gently in order to avoid excessive bending of the anesthesia needle being inserted through such tubes. If the curvature of the guide tubes is moderate as shown, friction resistance to passage of the needle through either tube will not be sufficient to require use of lubricant. In the fully inserted position of the

needle in a guide tube the needle tip should ordinarily project about one-half inch beyond the distal opening of such guide tube. Abutment of the hilt in the needle against the receiving end of the guide tube serves the gauging function of establishing the depth of penetration of the needle tip into the cavity wall tissue. The guide tubes 16 and 18 in the example are approximately five and one-half inches long, and an anesthesia needle used with such a device preferably would be approximately six inches in length. The locating aperture 12b may vary somewhat in size and form, but in the example is about five-eighths of an inch in diameter and circular. The distal ends of the respective guide tubes are situated about seven-eighths of an inch apart and located on a transverse line which is approximately tangential to the forward or tip edge of the locating aperture 12b. The purpose of bowing the guide tubes 16 and 18, as viewed in Figure 1, is to dispose the distal end portions of such tubes at a substantial incline to the birth canal wall area contacted by the head portion 12b, thereby insuring direct penetration of the needle tip to the required depth in the wall tissue as desired.

Referring to the sequence of operational views, Figures 4 through 7, the first step taken by the doctor in using 25 the instrument is to locate the tip of the middle finger of one hand in contact with the spine of the ischium I, as shown in Figure 4. In this figure the fingertip T of the doctor's left hand is placed in contact with the ischial spine I on the left side of the patient, with the 30 palm of the hand facing toward the left thigh. Since the ischial spine is a bony prominence very easily reached and located by palpation through the vagina, this initial step consumes very little time.

The second step, as shown in Figure 5, is to introduce 35 the head portion of the instrument into the birth canal by sliding it first along the palm of the hand and then along the palpitory finger, using the tip recess 12a to guide the head portion 12 lengthwise along the face of the correct finger as the instrument is being inserted. For 40 this purpose the convex side of the head portion 12 necessarily faces toward the left thigh of the patient. The shank or handle portion 14, is formed to be grasped in the doctor's right hand in order to advance the instrument the necessary distance. In Figure 6 the relationship between the palpitory finger T and the recessed tip 12a during insertion of the instrument is illustrated with greater clarity.

During the insertion movement of the instrument the palpitory finger T remains in contact with the ischial spine I. When the recessed tip 12a reaches the point 50 of contact, it necessarily wedges itself between the fingertip and the ischial spine. However, by holding the palpitory hand steady during further advance of the instrument the locating aperture 12b will soon come into registry with the fingertip and the latter will be permitted 55 to drop back into contact with the ischial spine I through the aperture 12b. The aperture 12b is of a sufficient size so that the ischial spine can readily be identified by palpation through such aperture with the instrument in the position shown in Figure 7, the operative position.

60 In the operative position of the instrument as shown in Figure 7, the bony prominence representing the ischial spine in effect serves as a locating element for the guide instrument, and it is found that when the locating aperture 12b of the instrument rests in registry with the ischial spine the distal opening of the lower guide tube (18a) in the example will, in practically all patients be correctly positioned to guide the projecting end of an anesthesia needle for injecting the pudendal nerve trunk. In Figure 7 it will be noted that the guide instrument in 65 its operative position may be held steady with the palpitory hand, which leaves the doctor's other hand free for the purpose of inserting the anesthesia needle N into the correct guide tube (18) for injecting the pudendal nerve. The lateral spacing of the two guide tubes intermediate 70 their ends permits them to traddle or embrace the palpa-

tory finger as an aid in steadying the instrument during insertion of the needle.

In order to inject the pudendal nerve trunk on the opposite side of the birth canal to complete the anesthesia, the instrument is retracted, turned about its longitudinal axis through 180°, and reinserted with the convex side of the retractor head portion 12 facing the right thigh of the patient. It is, of course, necessary for the doctor in this case to use his right hand as the palpatory hand and the left hand as the assist. In this case the guide tube 16 assumes the correct position for injecting the main trunk of the pudendal nerve on the right side of the birth canal.

From the above description it will be evident that the desired result of locating the distal end of a guide tube or equivalent guide member at the correct injection point palpable through the opening of a body cavity is accomplished by a locating element connected to the distal end portion of the guide tube and placed in a definite reference position by a process of palpation through such cavity opening. The opposite end portion of the guide tube (i. e. that into which the needle is inserted for injection purposes) has associated with it a suitable handle means or support for guiding the distal end portion to the correct operating location. In the example two guide members in the form of tubular members are used and are interconnected and supported by a retractor device having a shank portion extending throughout the length of the instrument and having a head portion interconnecting the distal end portion of the guide tubes and furnishing locating elements for the proper positioning of the respective tubes on the opposite lateral walls of the patient's birth canal. However, the details of construction may vary even for the illustrated application and may vary also for other applications of the invention in the field of obstetrical use as well as other usages which from a basic standpoint may include rectal, oral or incisional-cavity wall subadjacent nerve anesthetization.

I claim as my invention:

1. Anesthesia needle guide means comprising, in combination, retractor means having a head portion adapted for insertion into a cavity of the body to a wall contacting position therein corresponding to the desired location of anesthetic injection in the cavity wall, and an elongated shank portion adjoining said head portion and formed to permit handling of said retractor means to effect said insertion, and an elongated needle guide member open at both ends and mounted on said retractor means in a position thereon extending generally along said shank portion, said guide member forming an anesthesia needle guide passage extending throughout the length of said guide member for insertion of an elongated anesthesia needle through said passage to emerge beyond the distal end thereof, said guide member distal end opening being operatively positioned in relation to said retractor means head portion for injection of the cavity wall contacted by said head portion.

2. Anesthesia needle guide means as defined in claim 1, wherein the guide member comprises a tube having its distal end secured to the retractor means head portion and its other end secured to the retractor means shank portion.

3. Anesthesia needle guide means as defined in claim 2, wherein the retractor means head portion has an opening therein offset laterally from the distal end of the guide member and of a size and form to permit palpatory contact of a fingertip with the cavity wall through said opening for the locating of said head portion and guide member distal end in operative positional relationship relative to such cavity wall.

4. Anesthesia needle guide means as defined in claim 1, wherein the retractor means head portion has an opening therein offset laterally from the distal end of the guide member and of a size and form to permit palpa-

tory contact of a fingertip with the cavity wall through said opening for the locating of said head portion and guide member distal end in operative positional relationship relative to such cavity wall.

5. The anesthesia needle guide means defined in claim 1, wherein the guide member is of a length sufficient to permit positioning of its distal end adjacent the ischial spine of the birth canal wall of a human female for injecting the subjacent pudendal nerve trunk, with the opposite end of said guide member projecting outwardly through the vaginal opening.

6. Anesthesia needle guide means comprising, in combination, retractor means having a head portion adapted for insertion into the birth canal to contact a lateral wall area therein at the location of the ischial spine, and an elongated shank portion adjoining said head portion and formed to permit handling of said retractor means to effect said insertion, and an elongated needle guide member open at both ends and mounted on said retractor means in a position thereon extending generally along said shank portion, said guide member forming an anesthesia needle guide passage extending throughout the length of said guide member for insertion of an elongated anesthesia needle through said passage to emerge beyond the distal end thereof, said guide member distal end opening being operatively positioned in relation to said retractor means head portion for injection of the main trunk of the pudendal nerve as the latter follows beneath the ischial spine to enter Alcock's canal.

7. Means for guiding an anesthesia needle into the birth canal of a patient for injecting the main trunk of the pudendal nerve where the latter follows beneath the ischial spine to enter Alcock's canal, said guide means comprising retractor means having a head portion and a shank portion joined to the base of said head portion for inserting said head portion through the vagina to the location of the ischial spine, the tip of said head portion having a recess therein for guiding said head portion slidably along the length of the obstetrician's palpatory

finger the tip of which has been placed in contact preliminarily with the ischial spine, said head portion having a locating opening therein registrable with said preplaced fingertip to indicate arrival of said retractor means in operative position, and an elongated needle guide member rigidly mounted on said retractor means to extend along said shank portion thereof, said guide member defining a passage both ends of which are open for insertion of an elongated anesthesia needle therethrough, the needle-receiving end of said guide member being accessible externally of the patient's vagina, and the distal end of said guide member being positioned on said head portion for injection of the pudendal nerve trunk as aforesaid with said retractor means thus operatively positioned and the anesthesia needle passed through said guide member passage.

8. The guide means defined in claim 7, wherein the locating opening in the retractor means head portion comprises an aperture in said head portion located generally intermediately between the recessed tip and the base of said head portion.

9. The guide means defined in claim 8, wherein the retractor means head portion is convexly rounded on the side thereof to contact the birth canal wall for pressing membranous tissue of the birth canal aside during insertion of the retractor means into operative position thereof.

10. Means for guiding an anesthesia needle into the birth canal of a patient for injecting the main trunk of the pudendal nerve where the latter follows beneath the ischial spine to enter Alcock's canal, said guide means comprising an elongated needle guide tube of a length sufficient for insertion of said guide tube through the vagina to place the distal end thereof in contact with the lateral wall of the birth canal in operative position thereon for guiding an anesthesia needle to the pudendal nerve trunk by insertion of such needle through the tube

and beyond such distal end, the opposite end of said guide tube having handle means associated therewith and being positioned accessibly for insertion of the needle into said guide tube exteriorly of the patient, and locating means connected to said distal end of said guide tube and formed to slidably engage a palpatory finger of the doctor and to be pressed thereby into contact with the ischial spine of the patient in the inserted position of said needle guide tube.

11. Means for guiding an anesthesia needle into the birth canal of a patient for injecting the main trunk of the pudendal nerve where the latter follows beneath the ischial spine to enter Alcock's canal on either lateral wall of the birth canal, said guide means comprising a pair of elongated needle guide tubes fixedly interconnected, extending in side-by-side relationship and of a length sufficient for insertion thereof through the vagina to place the distal end of one such tube in contact with the lateral wall of the birth canal in operative position thereon for guiding an anesthesia needle to the pudendal nerve trunk by insertion of such needle through the tube and beyond such distal end, the opposite end of said guide tubes hav-

ing handle means associated therewith and being positioned accessibly for insertion of the needle into said guide tube exteriorly of the patient, and locating means mounted between the distal ends of said guide tubes and formed to slidably engage a palpatory finger of the doctor and to be pressed thereby into contact with the ischial spine on either lateral wall of the birth canal of the patient in the inserted position of said needle guide tubes and thereby locate the distal end of one guide tube or the other in operative position in relation to one lateral wall or the other of the birth canal.

12. The guide means defined in claim 11, wherein the locating means comprises a concavo-convex member having a recessed tip formed to be guided for sliding along the palpatory finger and having an intermediately situated opening formed generally in the base of the cavity for application of the tip of such finger against the ischial spine through such opening, thereby to locate one of the guide tubes in its operative position.
